(57) **CLAIM**

I claim the ornamental design for a lamp, as shown.

DESCRIPTION

FIG. 1 is an isometric view of the novel lamp design.

FIG. 2 is a right elevational view of the lamp shown in FIG. 1.

FIG. 3 is a left elevational view of the lamp shown in FIGS. 1 and 2.

FIG. 4 is a front elevational view of the lamp shown in FIGS. 1-3.

FIG. 5 is a rear elevational view of the lamp shown in FIGS. 1-4.

FIG. 6 is a top plan view of the lamp shown in FIGS. 1-5; and,

FIG. 7 is a bottom plan view of the lamp shown in FIGS. 1-6.

The broken lines shown are for illustrative purposes only and form no part of the claimed design.
